DESIGN FOR A COMBINED LIQUOR COOLING AND DISPLAY STAND

Murray M. Fibus, Youngstown, Ohio

Application January 19, 1943, Serial No. 109,308

Term of patent 14 years

(Cl. D80—2)

To all whom it may concern:

Be it known That I, Murray M. Fibus, a citizen of the United States, residing in Youngstown, county of Mahoning, State of Ohio, have invented a new, original, and ornamental Design for a Combined Liquor Cooling and Display Stand, of which the following is a specification, reference being had to the accompanying drawing, forming a part thereof.

The figure is a perspective view of a combined liquor cooling and display stand, showing my new design. The back, not shown in the drawing, is substantially plain.

I claim:

The ornamental design for a combined liquor cooling and display stand, as shown and described.

MURRAY M. FIBUS.
